(57) **CLAIM**

The ornamental design for a lamp, as shown and described above.

DESCRIPTION

FIG. 1 is a bottom perspective view of a lamp of the present invention;

FIG. 2 is a bottom perspective view of a second exemplary embodiment of a lamp of the present invention;

FIG. 3 is a top perspective view of either of the FIG. 1 and FIG. 2 embodiments;

FIG. 4 is a front elevation view of the FIG. 1 and FIG. 2 embodiments;

FIG. 5 is a back elevation view of the FIG. 1 and FIG. 2 embodiments;

FIG. 6 is a right side elevation view of the FIG. 1 and FIG. 2 embodiments;

FIG. 7 is a left side elevation view of the FIG. 1 and FIG. 2 embodiments;

FIG. 8 is a top plan view of the FIG. 1 and FIG. 2 embodiments;

FIG. 9 is a bottom plan view of the FIG. 2 embodiment;

FIG. 10 is a bottom perspective view of the FIG. 1 embodiment, with an addition of an optional shading element;

FIG. 11 is a front elevation view of the FIG. 10 embodiment;

FIG. 12 is a rear elevation view of the FIG. 10 embodiment; and,

FIG. 13 is a right side elevation view of the FIG. 10 embodiment.

The broken lines are for illustration only and form no part of the claimed design.
